ELECTRIC HEATING SYSTEM FOR OVENS

Francis H. McCormick, Dayton, Ohio, assignor to
General Motors Corporation, Dayton, Ohio, a
corporation of Delaware

Application February 17, 1940, Serial No. 319,519

14 Claims. (Cl. 219—20)

1

This invention relates to a domestic appliance and more particularly to plural unit electric oven heating systems providing an automatic change from preheat to bake circuit arrangement.

It is an object of my invention to provide for a plural unit oven, improved oven heating circuits including an automatic control providing an automatic change from high heat in both the upper and lower portions of the oven to a low heat in the upper portion and a high heat in the lower portion of the oven, and to so design the circuit and to so place the thermostat control in the circuit that the disconnecting of only one conductor by the thermostat control will safely deenergize the entire heating circuit.

It is another object of my invention to provide a simplified control for a plural unit electric oven providing an automatic change from preheat to bake circuit arrangement.

It is still another object of my invention to provide a plural unit oven circuit arrangement, in which an upper unit is fed from a tap on the lower unit for baking, when a control providing an automatic change from preheat to bake circuit arrangement.

It is still another object of my invention to provide an electric oven heating system in which a simple electro-thermal control holds the preheat circuit closed and provides an automatic change to bake circuit arrangement under the control of the thermostat.

Further objects and advantages of the present invention will be apparent from the following description, reference being had to the accompanying drawings, wherein a preferred form of the present invention is clearly shown.

In the drawings:

Fig. 1 is a view partly in section and partly diagrammatic of a two-unit electric oven heating system including an automatic control embodying one form of my invention;

Fig. 2 is a top view of the control knob and dial as shown in Fig. 1;

Fig. 3 is a top view of the upper cam shown in Fig. 1;

Fig. 4 is a top view of the lower cam shown in Fig. 1;

Fig. 5 is a simple wiring diagram of the electrical circuits shown in Fig. 1;

Fig. 6 is a view partly in section and partly diagrammatic of a modified two-unit electric oven heating system including a modified automatic mechanically interlocked control embodying another form of my invention;

2

Fig. 7 is a top view of the control knob and dial shown in Fig. 6;

Fig. 8 is a top view of the upper cam shown in Fig. 6;

Fig. 9 is a top view of the lower cam shown in Fig. 6;

Fig. 10 is a simple wiring diagram of the electric circuit shown in Fig. 6;

Fig. 11 is a modified simple wiring diagram showing a modification of the electric circuits and supply conductors shown in Fig. 6;

Fig. 12 is a view partly in section and partly diagrammatic of another modified two-unit oven heating system including another modified automatic control embodied in my invention; and

Fig. 13 is a fragmentary view of the preheat-bake control similar to that shown in Fig. 12, but in the latched position assumed at the instant the control knob is turned to "broil" position.

Referring now to the drawings and more particularly to Fig. 1, there is shown an electric oven heating system for a two-unit oven designated by the reference character 20 provided

25 with an upper heating unit 22 primarily for broiling, and a lower heating unit 24 primarily for baking. Both the upper and lower units 22 and 24 are connected by a single common conductor 26 to a thermostat provided with a movable contact 28 and a stationary contact 30.

The stationary contact 30 is connected by a conductor 32 to one conductor of a power source. The contacts 28 and 30 are opened and closed in accordance with the temperature of a thermostat bulb 34 which is located within the oven 20. These contacts are also employed to deenergize the entire system when the oven is not used.

The thermostat includes a housing 43 provided with an opening which receives a bushing 49 which is rigidly secured to the edges of the opening. This bushing 49 is internally threaded in order to receive in threaded engagement, the threaded adjusting screw 47. The inner end of the screw 47 engages a stud 40 which is attached to the expandable and contractible diaphragm 41. The interior of the diaphragm 41 is in communication with a capillary tube 42 which in turn is in communication with the interior of the bulb 34. A contractible and expandible liquid is provided in the bulb and the capillary tube 42 so that upon expansion of the liquid as a result of the heat to which the bulb is subjected, the liquid will be forced through the tube into the expandable and contractible diaphragm means 41. A tip 39 is provided on the face of

the diaphragm opposite the stud 40 to facilitate the transmission of the expansive forces of the diaphragm to the operating levers.

The tip 39 abuts a projection 44 upon the operating lever 46. The operating lever 46 has a knife edge which is seated in a notch of a bearing bracket 48 secured to the wall of the housing 43. A light coil spring 45 is provided for keeping the projection 44 in engagement with the tip 39. The other end of the operating lever 46 is provided with an aperture receiving the hooked end of a toggle tension spring 53. The other end of the toggle tension spring 53 is hooked through an aperture in a contact arm 55 which has its one end provided with a knife edge held by a stationary notched support 57. The other end of the contact arm 55 carries the thermostat contact 28 through a spring connection. The movement of the contact arm 55 and the contact 28 away from the contact 30 is limited by a stop 56.

The screw 47 is turned by an adjusting knob 48 in order to set the thermostat to open and close at any desired temperature of the thermostat bulb 34. The knob 48 is fastened by a set-screw 60 to a sleeve 62 which in turn is provided with a plate 64 carrying a slot which receives the pin 66 projecting from the screw 47. The plate 64 is fastened to the sleeve 62 by screws 68 which extend through adjusting slots in the plate 64. The sleeve 62 rotates upon the outside of the bushing 49 and carries an indicating dial 70. This sleeve 62 also carries an upper cam 72 and a lower cam 74, each of which is fixed to the sleeve 62.

The upper cam 72 actuates a push rod 76 which is normally held against the cam by a spring 78. The other end of the push rod 76 is adapted to engage a spring strip 80 which is anchored at its opposite end to an anchorage 82. This spring strip 80 is normally tensioned to hold a movable contact 84 in engagement with a stationary contact 86. The closing of the contacts 84 and 86 connects the other conductor 88 of the supply source through the conductor 90, the contacts 86 and 84 and through a conductor 92 to the other terminal of the lower oven heating unit 24.

For baking purposes, the other terminal of the upper heating unit 22 is connected through the conductor 94, the bimetal strip 96, the double contact 98, stationary contact 101 and the conductor 103 with a tap 105 upon the lower unit 24. This tap 105 divides the lower unit into sections 23 and 25 and is so located in the lower unit 24 that the voltage which is applied to the upper unit 22 is just sufficient to provide substantially uniform temperatures within the oven when the lower unit 24 is energized at full voltage. Normally, this point should be so located that about one-third the full voltage is applied to the upper unit 22. This, however, depends upon the resistance of the upper unit 22. With this arrangement, the upper unit 22 is placed in parallel with section 23 and in series with section 25. The bimetal strip 96 is so selected and formed that when it is at any room temperature the contact 98 will be firmly held in engagement with the contact 101.

For rapidly bringing the oven to the desired temperature prior to baking, a more rapid pre-heating circuit arrangement is provided. For this purpose, the bimetal strip 96 is provided with an operating knob 107 by which the bimetal strip 96 may be moved to place contact 98 in engagement with the stationary contact 109. The contact 109 is connected to a heater 111 which will heat the bimetal strip 96 and cause the contact 98 to remain in contact with the stationary con-

tact 109 as long as the heater 111 remains energized. The heater 111 is preferably placed sufficiently close to the bimetal 96 and has sufficient capacity that it will rapidly heat the bimetal 96 and will almost instantaneously hold the contact 98 against the stationary contact 109. If desired, an electromagnet may be substituted for the heater 111 and the bimetal strip be replaced by an armature biased to close the contacts 98 and 101.

The other end of the heater 111 is connected directly to the conductor 88. This then connects the conductor 88 through the heater 111, the contacts 109 and 98 and through the bimetal 96 and the conductor 94 with one terminal of the upper unit 22 while the other terminal of the upper unit 22 is connected through the conductor 26, the contacts 28 and 30 with the other supply conductor 32. Thus, in the preheat circuit arrangement, the upper unit 22 is directly connected across the supply conductors at full voltage, as is the lower unit 24, which has its output reduced by the change since no current is supplied from the tap to the upper unit 22. The contacts 98 and 109 will remain in engagement until the thermostat bulb 34 reaches the temperature for which the adjusting knob 48 of the thermostat is set.

At this temperature, the expansion of the diaphragm 41 will separate the contacts 28 and 30, thereby deenergizing all circuits. This will deenergize the heater 111 and allow the bimetal strip 96 to cool. Upon cooling, the contact 98 will return to its engagement with the stationary contact 101, thereby restoring the system to the bake circuit arrangement in which it will remain during succeeding cycles of the thermostat contacts 28 and 30. Thus, in this simple way, an automatic change from preheat to bake circuit arrangement is accomplished at the end of the preheat cycle. This is performed without any load upon the thermostat so that the sensitivity of the thermostat is not affected. Also, the bimetal device is simple, noiseless and substantially foolproof.

For broiling, the upper and lower cams 72 and 74 respectively, are used to separate the switch contacts 84 and 86 and to close the contacts 98 and 109. For this purpose, the cam 72 is provided with a raised or hump portion 121. When the knob 48 is rotated to set the broil legend opposite the indicator for the dial 70, the raised or hump portion 121 of the cam 72 will engage and push outwardly the end of the rod 76 so that the spring strip 80 will be deflected outwardly to separate the contacts 84 and 86. At the same time, the lower cam 74 will be rotated to place a recessed portion 123 in registration with a lower cam follower push rod 125 which extends through the end of the bimetal strip 96 and is provided with a collar 127 on the far side and a collar 129 on the near side. The movement of the lower cam push rod 125 into the recess 123 under the influence of the follower spring 131 causes the collar 127 to move the free end of the bimetal strip 96 to the right so that the contact 98 will be held in engagement with the stationary contact 109.

This movement of the knob 48 to the "broil" position thus connects the upper unit 22 across full voltage and disconnects the lower unit 24 at the one terminal and also its tap 105. The circuit for broiling includes the source conductor 88, the heater 111, the stationary contact 109, the movable contact 98, the bimetal strip 96, the conductor 94, the upper unit 22, the con-

ductor 26, the movable contact 28, the stationary contact 30 and the source conductor 32. The knob 48 is turned sufficiently far to attain the "broil" position that the thermostat is set at a temperature sufficiently high to maintain the thermostat contacts closed for a sufficient length of time for broiling purposes. Ordinarily, the oven door is left open to prevent the oven temperatures from rising sufficiently high to open the thermostat contacts. No current flows through the lower unit 24 because the conductor 92 at its one terminal is disconnected by the opening of the contacts 84 and 86 and the conductor 103 which is connected to the top 105 is disconnected by the movement of the contact 98 away from the contact 101.

When the knob 48 is turned substantially 360 degrees in the opposite direction to the "off" position, the upper cam 72 is turned so that a second raised portion 133 will engage the upper cam push rod 76 to again open the contacts 84 and 86. Likewise, the cam 74 will present a raised portion 135 to the lower cam push rod 125 so that the shoulder 129 will engage the bimetal strip 96 to separate the contacts 98 and 109, if they should happen to be engaged. This movement of the knob 48 to the "off" position, will also open the thermostat contacts so that both sides of all circuits will be disconnected from the source conductors. This will provide positive assurance against any live conductors when the switch is turned to the "off" position.

However, this is not absolutely necessary, since the breaking of one side of the line is sufficient in this circuit, since only two source conductors are employed. If desired, the push rod 125 and its cam may be eliminated and the knob 107 be used to move the bimetal element 96 to "preheat" position when the knob 48 is turned to the "broil" position for broiling purposes. With such a system, the bimetal 96 would naturally move when cooled to separate the contacts 98 and 109, since the thermostat contacts 28 and 36 would be open in the "off" position.

In Fig. 6 is shown a system in which the operation of the thermostat to open position mechanically changes a double throw switch from "preheat" to "bake" position at the end of the first heating cycle. In this form, the control knob sets the preheat double throw switch as well as provides the bake and broil circuit arrangements. In Fig. 6, there is shown a two-unit oven designated by the reference character 220 including an upper heating unit 222, primarily for broiling, and a lower heating unit 224, primarily for baking. Both the upper and lower units 222 and 224 are connected by a single common conductor 226 to a thermostat provided with a movable contact 228 and a stationary contact 230. The stationary contact 230 is connected by a conductor 232 to one conductor of a power source. The contacts 228 and 230 are opened and closed in accordance with the temperature of a thermostat bulb 234 which is located within the oven 220. These contacts are also employed to deenergize the entire system when the oven is not used.

The thermostat includes a housing 243 which rigidly supports the bushing 249 which threadedly receives the control knob mechanism, similar to that shown in Fig. 1. The rotation of the control knob 248 changes the position of the inner end of the screw 247 which engages a stud attached to the expansible and contractible diaphragm 241. The interior of the diaphragm 241 is in communication with a capillary tube 242 75

which in turn is in communication with the interior of the bulb 234. A contractible and expansible liquid is provided in the bulb and the capillary tube 242 so that upon expansion of the liquid as a result of the heat to which the bulb is subjected, the liquid will be forced through the tube into the expansible and contractible diaphragm means 241.

A tip, provided upon the face of diaphragm 10 241 opposite the stud, abuts a projection upon operating lever 246. The operating lever 246 is pivoted at one end and is connected at the other end to a light toggle spring 245 which has its other end connected to a pivoted contact arm 255 carrying the movable contact 228. The contact arm 255 is limited in its opening movement by a stop 256. The screw 247 is turned by the adjusting knob 248 in order to set the thermostat to open and close at any desired temperature of the thermostat bulb 234.

Beneath the knob 248 is an upper cam 272 which rotates with the knob 248 and actuates a push rod 276 which is normally held against the cam by a spring 278. The other end of the push rod 276 is adapted to engage the spring strip 280 which is normally tensioned to hold the movable contact 284 in engagement with stationary contact 286. The closing of the contacts 284 and 286 connects the other conductor 288 of the supply source to the other terminal of the lower oven heating unit 224 through the conductor 290, the contacts 286 and 284 and the conductor 292.

For banking purposes, the other terminal of the upper heating unit 222 is connected through 35 a conductor 294, to a contact arm 296 carrying a double contact 298, normally in contact with a stationary contact 301 connected by the conductor 303 with a tap 305 upon the lower unit 224. This tap 305 divides the lower unit into sections 40 223 and 225 and is so located in the lower unit 224 that the voltage applied to the upper unit 222 is just sufficient to provide substantially uniform heating and uniform temperatures within the oven when the lower unit 224 is energized at full voltage. In the normal oven, this point ordinarily falls so that the section 223 includes about one-third the total resistance of the lower unit 224. The contact arm 296 is pivoted at the end opposite the double contact 298 and is provided 50 with a tension toggle spring 300 for keeping the double contact 298 either in engagement with the stationary contact 301 or a stationary contact 309.

For rapidly preheating the oven, the knob 248 is first turned to the "broil" position. This brings into operation the lower cam 274 which, like the upper cam 272, rotates with the knob 248. This lower cam 274 actuates a push rod 325 which is normally held against cam 274 by a follower spring 331.

In order to provide an automatic preheat cycle prior to a normal baking cycle, the knob 248 is first turned to the "broil" position and thereafter is immediately turned back to the baking temperature desired. When the knob 248 is turned to the "broil" position, the cam 274 will present a raised portion 323 to the adjacent end of the cam follower push rod 325. This will cause the cam surface 327 upon the push rod 325 to lift the vertical operating bar 329 until its hooked lower end raises the contact arm 296 across its dead center position so that the double contact 298 will then move into and be held in engagement with the stationary contact 309 by the toggle spring 300. This connects the one

terminal of the upper unit 224 and the conductor 294 through the contact 298 and the contact 309 directly to the source conductor 288 instead of the tap 305. This, therefore, will connect the upper unit 222 across full voltage, thereby greatly increasing its output for rapid preheating purposes prior to baking.

The contact 298 will remain in contact with the stationary contact 309 until the thermostat bulb 234 reaches the baking temperature for which the adjusting knob 248 of the thermostat is set. At this time, the contacts 228 and 230 will be separated and the contact arm 255 will move downwardly carrying with it a pin 219 which will strike the contact arm 296 to separate the contact 298 from the contact 309 and to overcome the force of the toggle spring 300 to move the double contact 298 into engagement with the contact 301. At this time, all the circuits of the system will be deenergized by the opening of the contacts 228 and 230. The contact 298 will remain in contact with the contact 301 throughout the succeeding cycles of the thermostat contacts 228 and 230 to maintain the proper baking circuit arrangement of the upper and lower units for baking purposes.

For broiling, the knob 248 is turned to the "broil" position and left in that position for the duration of the broiling operation. As mentioned before, this will throw the contact 298 into contact with the stationary contact 309 to connect the upper unit 222 directly across the supply conductors 288 and 232. At the same time, the upper cam 272 will present a raised portion 321 which will push the push rod 276 outwardly to separate the contacts 284 and 286 to deenergize the lower unit 224. In the broil position, the thermostat is adjusted to a sufficiently high operating temperature to prevent cycling.

When the knob 248 is turned to the "off" position, the thermostat contacts 228 and 230 will be opened and the contact arm 255 will cause the pin 219 to engage the contact arm 296 to move the contact 298 again into contact with the stationary contact 301. However, the cam 272 is provided with a second raised portion 333 which will push the push rod 276 outwardly in the "off" position of the knob 248, to separate the contacts 286 and 284. This insures positive deenergization of the entire system.

The advantage of opening these contacts in the "off" position is illustrated in Fig. 11 in which the contact 301 is connected to a neutral (ground) conductor 302 instead of by the conductor 303 to the tap 305. Otherwise, the circuit shown in Fig. 11 is exactly like the circuit shown in Figs. 6 and 10 and all the other elements are identical. However, it will be seen that by opening the contacts 284 and 286 as well as moving contact 298 into contact with the contact 301 and by opening the single thermostat contacts 228 and 230 in the "off" position, all parts of the system are safely deenergized and only a single set of simple contacts is required for the thermostat, even though the three-wire Edison circuit is used as a source.

In Figs. 12 and 13, there is shown another modified form which is substantially identical to the form shown in Figs. 1 to 5 excepting that the preheat is actuated as in Figs. 6 to 10 by first moving the regulating knob to the "broil" position and thence to the baking temperature desired, and excepting that a latch is also provided for instantaneously holding the bimetal in "pre-

heat" position until the bimetal is sufficiently heated to remain in the "preheat" position.

Referring now more particularly to Figs. 12 and 13, there is shown a control knob 448 provided with an upper cam 472 and a lower cam 474 which, through a primary lever 446 and a toggle spring 453, operates the pivoted contact arm 455 to open and close the thermostat contacts 428 and 430. The thermostat contacts 428 and 430 connect the conductor 432 with a conductor 426 which connects with one terminal of the heating unit 422 and one terminal of the lower heating unit 424. These terminal are located within an oven indicated diagrammatically and designated by the reference character 420. The upper cam 472 operates a push rod 476 to open the contacts 484 and 486 in the "broil" and "off" positions of the knob 448. The knob 448 is provided with legends upon its dial as shown in Fig. 2. The contacts 486 and 484 connect the source conductor 488 and the conductor 490 to the conductor 492 which connects to the other terminal of the lower unit 424.

The double throw bake and preheat switch includes a bimetal element 496 which carries a double contact 498. This bimetal element is so formed that at ordinary temperatures, it normally holds the contact 498 in engagement with a stationary contact 501. This connects the upper heating unit 422 with the tap 505 on the lower unit. The circuit for the upper unit 422 in the bake circuit arrangement thus includes the source conductor 432, the contacts 430 and 428, the conductor 426, the upper heating unit 422, the conductor 494, the bimetal element 496, contacts 498 and 501, the conductor 503, the tap 505, the section 425 of the lower unit 424, the conductor 492, the contacts 484 and 486, the conductor 490 and the source conductor 488.

For "preheat" purposes, the knob 448 is first turned to the "broil" position and then turned to one of the baking temperature positions. The turning of the knob 448 to the "broil" position causes the cam follower 525 to engage the recess 123 in the cam 474 to retract the follower 525 under the influence of the follower spring 531 in order to cause the cam shoulder 527 to engage the bimetal element 496 and to pull the bimetal element 496 into the position shown in Fig. 13 where the upper end of the bimetal 496 will ride over and be caught by the catch 551 on a second bimetal member 553 which is anchored to the support 555. This will close a circuit which includes the source conductor 488, the conductor 559, an electric heater 557 for heating the bimetal 553, a conductor 512, the electric heater 511, (corresponding to the heater 111 of Fig. 1), the contact 509, the contact 498, the bimetal element 496, the conductor 494 which connects to one terminal of the upper heating unit 422 having its other terminal connected to the conductor 426, the contacts 428 and 430 and the source conductor 432.

The bimetal 553 assumes a lower position when at room temperature as shown in both Figs. 12 and 13, but when heated by the electric heater 557, it curls upwardly to the dotted position shown in Fig. 13, so that the bimetal 496 is unlatched. However, as long as the thermostat contacts 428 and 430 and contacts 498 and 509 remain closed, the heater 511 will keep the bimetal 496 heated with the contact 498 in contact with the stationary contact 509. However, when the thermostat control bulb 434 connected to the di-

aphram 441 reaches the temperature for which the knob 488 is set, the thermostat contacts 428 and 430 will open, thus deenergizing the entire system including the electric heater 511. This will allow the bimetal 496 to cool and to move the contact 498 into contact with the stationary contact without interference from the catch 551 which is so constructed that it will not cool as rapidly as the bimetal 496. For this purpose, the bimetal 553 may be made wider or of heavier metal or may have additional metal attached thereto in order to make it cool more slowly than the bimetal 496.

When the control knob 448 is turned to the "off" position, the upper cam 472 will separate the contacts 484 and 486, while the lower cam 474 will move the push rod 525 outwardly to cause the shoulder 529 to engage and move the bimetal element 496 so that the contact 498 will be positively held in engagement with the stationary contact 501. Normally, after the first few seconds of the preheat cycle, the bimetal 553 will be bent upwardly by the heat applied to it by the heater 557 so that the bimetal 496 may be moved at any time thereafter without interference from the catch 551. However, if the knob 448 should be returned to the "off" position before the bimetal 553 is heated sufficiently when the knob has been in "preheat" or "broil" position, the shoulder 557 upon the push rod 525 will move outwardly and will engage a cam 561 provided upon the end of the bimetal member 553 so that the coaction of the cam surface upon the shoulder 527 with the cam 561 will raise the bimetal member 553, thereby releasing the catch from the end of the bimetal member 496 prior to the time the shoulder 529 engages the bimetal 496 to move it positively to its baking position. Thus, the system provides a single knob control for all positions including the actuation of a simple bimetal preheat bake switch which can be instantaneously latched in preheat position. Also, in this system, all contacts are opened when the knob is turned to the "off" position so that complete safety is assured.

While the form of embodiment of the invention as herein disclosed, constitutes a preferred form, it is to be understood that other forms might be adopted, all coming within the scope of the claims which follow.

What is claimed is as follows:

1. An electric oven heating system including an upper oven heating means, a lower oven heating means, a thermostat switch mechanism for connecting and disconnecting one terminal of the upper and lower heating means to and from one conductor of an electrical power source, said lower heating means being provided with a tap at an intermediate point thereon, switch means for connecting and disconnecting the other terminal of said upper heating means to and from said tap, switch means for connecting and disconnecting said other terminal of said upper heating unit to and from a second conductor of said power source, means for connecting said other terminal of said lower heating means to said power source, and means controlled by said thermostat switch mechanism for disconnecting said other conductor of said source from said other terminal of the upper heating means and connecting said other terminal to said tap.

2. An electric oven heating system including an upper oven heating means, a lower oven heating means, a thermostat switch mechanism for connecting and disconnecting one terminal of the

upper and lower heating means to and from one conductor of an electrical power source, said lower heating means being provided with a tap at an intermediate point thereon, switch means for connecting and disconnecting the other terminal of said upper heating means to and from said tap, switch means for connecting and disconnecting said other terminal of said upper heating unit to and from a second conductor of said power source, means for connecting said other terminal of said lower heating means to said power source, and means controlled by said thermostat switch mechanism for disconnecting said other conductor of said source from said other terminal of the upper heating means and connecting said other terminal to said tap, means for closing one of said switch means and opening the other to disconnect said other terminal of said upper heating means from said tap and connecting said other terminal to said second conductor of said power source, and means for disconnecting said other terminal of said lower heating means from said second conductor of said power source for broiling purposes.

3. An electric oven heating system including an upper oven heating means, a lower oven heating means, a thermostat switch mechanism for connecting and disconnecting one terminal of the upper and lower heating means to and from one conductor of an electrical power source, said lower heating means being provided with a tap at an intermediate point thereon, switch means for connecting and disconnecting the other terminal of said upper heating means to and from said tap, switch means for connecting and disconnecting said other terminal of said upper heating unit to and from a second conductor of said power source, means for connecting said other terminal of said lower heating means to said power source, and means controlled by said thermostat switch mechanism for disconnecting said other conductor of said source from said other terminal of the upper heating means and connecting said other terminal to said tap, means for closing one of said switch means and opening the other to disconnect said other terminal of said upper heating means from said tap and connecting said other terminal to said second conductor of said power source, and means for disconnecting said other terminal of said lower heating means from said tap, means for closing one of said switch means and opening the other to disconnect said other terminal of said upper heating means from said tap and connecting said other terminal to said second conductor of said power source for broiling purposes.

4. An electric oven heating system including an upper oven heating means, a lower oven heating means, a thermostat switch mechanism for connecting and disconnecting one terminal of the upper and lower heating means to and from one conductor of an electrical power source, said lower heating means being provided with a tap at an intermediate point thereon; a double throw switch having one contact connected to said tap, another contact connected to a second conductor of said source, and the double contact to said other terminal of said upper heating means, means for connecting the other terminal of said lower heating means to said second conductor of said power source, and means controlled by said thermostat switch mechanism for operating said double throw switch.

5. An electric oven heating system including an upper oven heating means, a lower oven heating means, a thermostat switch mechanism for connecting and disconnecting one terminal of the

upper and lower heating means to and from one conductor of an electrical power source, said lower heating means being provided with a tap at an intermediate point thereon; a double throw switch having one contact connected to said tap, another contact connected to a second conductor of said source, and the double contact to said other terminal of said upper heating means, means for connecting the other terminal of said lower heating means to said second conductor of said power source, means for said double throw switch for normally holding it in one position providing a connection between said other terminal of said upper heating means and said tap, and electrically operated means for holding said double throw switch in a second position connecting said other terminal and said second conductor.

6. An electric oven heating system including an upper oven heating means, a lower oven heating means, a thermostat switch mechanism for connecting and disconnecting one terminal of the upper and lower heating means to and from one conductor of an electrical power source, said lower heating means being provided with a tap at an intermediate point thereon; a double throw switch having one contact connected to said tap, another contact connected to a second conductor of said source, and the double contact to said other terminal of said upper heating means, means for connecting the other terminal of said lower heating means to said second conductor of said power source, means for said double throw switch for normally holding it in one position, providing a connection between said other terminal of said upper heating means and said tap, and electrically operated means connected in series with said another contact for holding said double throw switch in a second position connecting said other terminal and said second conductor.

7. An electric oven heating system including upper and lower oven heating means, control means having "off," "preheat," "bake" and "broil" positions, said control means including means for disconnecting one terminal of said lower heating means in "off" and "broil" positions and connecting said terminal to a source conductor in "preheat" and "bake" positions, said control means including a control device connected to one terminal of the upper heating means and having a normal "bake" position normally providing a bake circuit arrangement energizing both heating means with the lower heating means energized at a higher voltage than the upper heating means, said control device also having a selective "preheat" position providing a preheat circuit arrangement in which the upper and lower heating means are energized at substantially the same voltage, said control means including a thermostatic device for changing said control device from "preheat" to "bake" position, said thermostatic device also including contacts connected to other terminals of said upper and lower heating means.

8. An electric oven heating system including upper and lower oven heating means, control means having "off," "preheat," "bake" and "broil" positions providing preheat, bake and broil circuit arrangements of the oven heating means in the respective positions and completely deenergizing said heating means in the "off" position, said upper and lower heating means being both energized at full wattage in said "preheat" position, said upper heating means being energized at reduced wattage with said lower heating means at full wattage in "bake" position,

and said upper heating means alone being energized in "broil" position, said control means including a selective double throw switch mechanism for changing the circuit arrangement from the preheat to bake arrangement and for selecting the preheat arrangement, said double throw switch being connected to one terminal of said upper heating means and to one source conductor, said control means including another switch means connected to one terminal of said lower heating means and to said one source conductor together with means for closing said another switch in the "bake" and "preheat" positions and opening said another switch in the "off" and "broil" positions, said control means also including a thermostatic switch for controlling the movement of the double throw switch to change the circuit arrangement from preheat to bake circuit arrangement, said thermostat switch having contacts connected to other terminals of said upper and lower heating means and to another conductor of said source, said thermostat being movable to separate its contacts in the "off" position.

25 9. An electric oven system adapted to be connected to two lines of a source of electric power comprising a unitary upper heating resistance, a series sectional lower heating resistance, thermostatic switch mechanism having knob means adapted to be placed in "off" temperature adjustable "bake," "broil" and "preheat" positions and having two single throw single contact arms and a double throw single contact arm so actuated by said knob means that said resistances are disconnected from said two lines in the "off" position, are placed in parallel across said lines in "preheat" position, are placed with the lower resistance across said lines and with the upper resistance across one of said lines and at the junction of the sections of said lower heating resistance in the "bake" position, and are placed with the upper heating resistance only across the lines in the "broil" position, the thermostatic switch mechanism automatically changing the setting from "preheat" to "bake" at the end of the preheating cycle.

10. An electric oven system adapted to be connected to two lines of a source of electric power comprising a unitary upper heating resistance, a series sectional lower heating resistance, thermostatic switch mechanism having knob means adapted to be placed in "off" temperature adjustable "bake," "broil" and "preheat" positions and having two single throw single contact arms and a double throw single contact arm so actuated by said knob means that said resistances are disconnected from said two lines in the "off" position, are placed in parallel across said lines in "preheat" position, are placed with the lower resistance across said lines and with the upper resistance across one of said lines and at the junction of the sections of said lower heating resistance in the "bake" position, and are placed with the upper heating resistance only across the lines in the "broil" position, the thermostatic switch mechanism automatically changing the setting from "preheat" to "bake" at the end of the preheating cycle by means of a heating device acting on one of said arms.

11. An electric oven system adapted to be connected to two lines of a source of electric power comprising a unitary upper heating resistance, a series sectional lower heating resistance, thermostatic switch mechanism having knob means adapted to be placed in "off" temperature adjust-

able "bake," "broil" and "preheat" positions and having two single throw single contact arms and a double throw single contact arm so actuated by said knob means that said resistances are disconnected from said two lines in the "off" position, are placed in parallel across said lines in "preheat" position, are placed with the lower resistance across said lines and with the upper resistance across one of said lines and at the junction of the sections of said lower heating resistance in the "bake" position, and are placed with the upper heating resistance only across the lines in the "broil" position, the thermostatic switch mechanism automatically changing the setting from "preheat" to "bake" at the end of the preheating cycle by means of a snap action spring on one of said arms actuated by another of said arms.

12. An electric oven system adapted to be connected to three lines of a source of electric power comprising a unitary upper heating resistance, a unitary lower heating resistance, thermostatic switch mechanism having knob means adapted to be placed in "off," temperature adjustable "bake" and "broil" positions and having two single throw single contact arms and a double throw single contact arm so actuated by said knob means that said resistances are disconnected from at least two of said lines in the "off" position, are placed in parallel across two of said lines at relatively high voltage upon manipulation from "broil" to "bake" positions, are placed with the lower resistance across two of said lines at relatively high voltage and with the upper resistance across one of said lines and the other of said lines at a relatively low voltage in the bake position, and with the upper resistance across two of said lines at relatively high voltage in the broil position, the thermostatic switch mechanism automatically changing the setting of the two resistances in parallel at relatively high voltage to the "bake" setting at the end of a preheating cycle.

13. An electric oven system adapted to be connected to three lines of a source of electric power comprising a unitary upper heating resistance, a unitary lower heating resistance, thermostatic switch mechanism having knob means adapted to be placed in "off" temperature adjustable "bake," and "broil" positions and having two single throw single contact arms and a double throw single contact arm so actuated by said

knob means that said resistances are disconnected from at least two of said lines in the "off" position, are placed in parallel across two of said lines at relatively high voltage upon manipulation from "broil" to "bake" positions, are placed with the lower resistance across two of said lines at relatively high voltage and with the upper resistance across one of said lines and the other of said lines at a relatively low voltage in the bake position, and with the upper resistance across two of said lines at relatively high voltage in the broil position, the thermostatic switch mechanism automatically changing the setting of the two resistances in parallel at relatively high voltage to the "bake" setting at the end of a preheating cycle by means of a snap action spring on one of said arms actuated by another of said arms.

14. An electric heating means for heating a zone to be heated, single pole thermostatic switch means for controlling the connection of the heating means to one live supply line of a power source to regulate the temperatures of said zone, connecting means for connecting said heating means selectively into a baking circuit arrangement and into a preheat circuit arrangement and including switch means controlling the connection to another live supply line of said power source, manually operable means having off and on positions for operating said connecting means to change from the baking circuit arrangement to the preheat circuit arrangement in the on position and disconnecting said live supply lines in the off position, and electrically operated means energized in response to the opening of said thermostatic switch means for controlling the operation of said connecting means to change from the preheat circuit arrangement to the baking circuit arrangement.
